UNITED STATES PATENT OFFICE

170,521

PIGGY BANK

Albert N. Brooks, Chicago, Ill.

Application April 1, 1952, Serial No. 19,151

Term of patent 7 years

(Cl. D34—11)

To all whom it may concern:

Be it known that I, Albert N. Brooks, a citizen of the United States, residing at Chicago, county of Cook and State of Illinois, have invented a new, original, and ornamental Design for Piggy Bank, of which the following is a specification, reference being had to the accompanying drawing forming a part thereof.

I claim:

The ornamental design for a piggy bank, as shown.

ALBERT N. BROOKS.
